UNITED STATES PATENT OFFICE.

CHARLES L. FINNEY, OF WYALUSING, PENNSYLVANIA, ASSIGNOR OF ONE-HALF TO L. R. LANTZ, OF WYALUSING, PENNSYLVANIA.

TARGET.

SPECIFICATION forming part of Letters Patent No. 722,220, dated March 10, 1903.

Application filed May 20, 1902. Serial No. 108,291. (No model.)

To all whom it may concern:

Be it known that I, CHARLES L. FINNEY, a citizen of the United States, residing at Wyalusing, in the county of Bradford and State of Pennsylvania, have invented certain new and useful Improvements in Targets, of which the following is a specification.

My invention relates to targets adapted for use in saber practice at cavalry drills; and its object is to provide an improved target of this class in which the target proper is held securely in place on its support and automatically returned to its normal position after being struck with the saber by the cavalry-

man.

Heretofore it has been necessary to have a number of men stationed at different points in the drill-hall, one behind each target to replace the same on its support when dislodged by a blow, and as the target was often rolled some distance from its support it could not be replaced in time for the next approaching cavalryman. The present invention is designed to obviate such inconvenience by providing means to automatically return the target to its normal position and at the same time render it so sensitive to the blow as to yield sufficiently to reduce the injury resulting therefrom to a minimum, and thus prolong the life of the target.

A further object is to provide a vertically-adjustable pedestal or support to adapt it for use at different elevations to represent a man in a reclining, kneeling, or standing position.

Other objects will appear as the nature of the invention is better understood, and the fundamental features involved in the construction, combination, and arrangement of parts are necessarily susceptible to a wide range of modification without departing from the spirit of the invention or sacrificing any of the advantages thereof.

In the accompanying drawings, forming part of this specification, Figure 1 is a perspective view of the device as it appears ready for use and showing in dotted lines the position of the target after being struck. Fig. 2 is a longitudinal vertical section of the same. Fig. 3 is a detail in perspective of the feet detached.

Like characters of reference indicate corresponding parts throughout the several views.

In carrying out my invention I provide a telescoping standard A, composed of a tubular base 1, provided with transverse intersecting recesses 2 at its bottom, in which are fitted removable feet 3, crossing each other at the center of the base and extending diametrically from each side thereof. The lower foot 4 has a pair of brackets 5 on its upper side, spaced apart a sufficient distance to permit the lower end of the base to be inserted therebetween, and to each cleat is secured a hook 6 or other fastening device to engage an eye 7 on opposite sides of the base. The upper movable foot 8 is confined in its recesses 2 by the lower foot 4 and has a recess 9 on its under side, intermediate its ends, to provide thickened end portions 10, which rest on the ground. This foot 8 is adapted to slide longitudinally, so that the end may be forced inwardly out of the path of the horses' feet, while the other end is projected on the opposite side to insure against accidental overturning of the base, and the shoulders formed by the thickened ends serve as stops. Secured to opposite sides of the base above the recesses are a pair of brackets 11, which present an extended bearing-surface for the sliding foot.

In the tubular base 1 is a telescoping tubular upright 12, having a head 13, provided with a central aperture 14, through which a rope or other flexible connection 15 passes. This rope carries a weight 16, which depends within the tubular upright 12, and its other end is secured to the lower end of the target. This head 13 consists of a disk having a diameter greater than the width of the upright 12, so that when the target is knocked to one side, as shown in dotted lines in Fig. 1, its spherical base 17 will roll thereon and be prevented from dropping down beside the upright, and thus the target is always in a position to be operated upon by the weight.

The target preferably consists of two spheres 17 and 18, connected by a stem 19. The upper sphere or head 18 is composed of some pliable material covered with leather and is designed to represent a man's head, while the lower sphere or base 17 is made of

wood or other hard substance. The bottom of this sphere 17 is flattened to provide a flat substantial bearing 20 for the target, and to this flattened portion is secured the end of 5 the rope. When the head 18 is struck, the target will fall to one side, as shown in dotted lines in Fig. 1; but the weight through its flexible connection 15 will cause the target to immediately right itself to a perpendicular 10 position. As the target will rock from side to side until it comes to a standstill, it will be evident to the judges and spectators that it was struck; but this rocking motion may be regulated by flattening the base of the 15 sphere 17 to a greater or less degree without destroying its yielding action. By this construction it will be seen that the target is held against dislodgment and automatically returned to its normal position when stabbed 20 or hit with a saber.

As it is customary to have the targets at different elevations to represent a man in a reclining, kneeling, or standing position, I provide a vertically-adjustable standard with 25 means to hold it in its adjusted position. This means consists of a rack 21, secured to one side of the telescoping upright 12 and adapted to be engaged by a pawl 22, playing through an opening 23 in the base 1 and secured to the 30 said base by a spring 24.

Having thus described my invention, what I claim, and desire to secure by Letters Patent, is—

1. In a device of the class described, a telescoping hollow standard, a movable target 35 detachably seated thereon, and means depending in the standard for holding the target seated and for automatically returning the same to its seat after being dislodged there- 40 from.

2. In a device of the class described, a telescoping hollow standard, a movable target supported thereon, a weight suspended in the standard, and a flexible connection between 45 the weight and the target, whereby the target is firmly supported and automatically returned to its normal position.

3. In a device of the class described, the combination of a vertically-adjustable stand- 50 ard having a head provided with an aperture, a movable target supported on said head and composed of two spheres connected by a rod, and a resetting device connected to the lower sphere and extending through said aperture 55 to automatically return the target to an upright position.

4. A target for cavalry practice composed of a base, a vertically adjustable, tubular upright mounted in said base, an oscillating tar- 60 get composed of two spheres, the lower one of which is yieldingly supported on the up-

right, and means in the upright to reset the target.

5. In a device of the class described, a base having feet detachably secured thereto, one 65 of which is slidable thereon to adapt it to be projected on either side thereof.

6. In a device of the class described, a base having transverse intersecting recesses, a sliding foot mounted in one of said recesses and 70 an intersecting foot detachably mounted in the other recess to hold the sliding foot in position.

7. In a device of the class described, a base having transverse intersecting recesses, an 75 upper sliding foot in one of said recesses, a lower detachable foot mounted in the other recess and provided with means to secure it to the base, said lower foot serving to hold the upper foot in its recess. 80

8. In a device of the class described, the combination of a standard composed of a tubular upright vertically adjustable in the base and provided with a head, a target posited on 85 said head and a resetting device extending through the head into the upright.

9. In a device of the class described, the combination of a standard composed of a tubular base and a tubular upright vertically adjustable in said base and provided with a head, 90 a target having a spherical base provided with a flattened bearing-surface and a resetting device extending through the head into the upright.

10. In a device of the class described, a telescoping hollow standard having a flat head, a target having a spherical base seated on said head and adapted to roll thereon when dislodged from its seat, and means depending in the standard to automatically reset the target. 95

11. In a device of the class described, a standard composed of a tubular base and a tubular upright vertically adjustable in said base, a rack on the upright, a spring on the base, a pawl on the spring to engage the rack, 105 a target detachably posited on the upright and means in the upright to reset the target.

12. The combination with a tubular standard, of a target yieldingly supported thereon and composed of an upper sphere adapted to 110 receive the blow, a lower sphere seated on the standard and a stem connecting the spheres, and means in the standard for holding the target in an upright position and for automatically returning it to such position after 115 being dislodged by the blow.

In testimony whereof I affix my signature in presence of two witnesses.

CHARLES L. FINNEY.
